L. P. WOOD

DUMPING BODY FOR TRUCKS AND WAGONS

Filed Feb. 3, 1925

Inventor
Louis P. Wood

By *Samuel Henick*,
Attorney

UNITED STATES PATENT OFFICE.

LOUIS P. WOOD, OF NISLAND, SOUTH DAKOTA.

DUMPING BODY FOR TRUCKS AND WAGONS.

Application filed February 3, 1925. Serial No. 6,643.

To all whom it may concern:

Be it known that LOUIS P. WOOD, a citizen of the United States, residing at Nisland, in the county of Butte and State of South Dakota, has invented certain new and useful Improvements in Dumping Bodies for Trucks and Wagons, of which the following is a specification.

This invention relates to a dumping body for trucks, and wagons and it has for its object to provide a device of this character adapted to be readily tipped to either side in such manner as to discharge its load upon either side of the line of travel of the vehicle.

Further objects and advantages of the invention will be set forth in the detailed description which follows:

In the accompanying drawings:

Figure 1 is a view in side elevation of a wagon constructed in accordance with the invention,

Figure 2 is a transverse sectional view, and

Figure 3 is a transverse sectional view showing the body tipped to the right.

Like numerals designate corresponding parts in all of the figures of the drawing:

The body proper comprises sills 5, bottom

6 and sides 7 and 8, the latter being hingedly connected to the sills at 9 and being adapted to swing downwardly in the manner illustrated at the right hand side of Figure 3. This hinging is effected by passing rods or pins 10 through the eyes of hinges 11 that are secured to the sides 7 and 8 and sills 5. Bolsters 12 at the front and rear ends of the body serve to support the body from a pivot rod 13, which extends from end to end of

the structure and is mounted in bearings or straps 14, which straps are in turn supported upon the cross bars 15 of a running gear 16.

Supporting panels 17 and 18 are hingedly mounted upon the side rails of the running gear 16, by hinges 19 and when these panels are swung upwardly to the position illus-

trated in Figure 2, their posts 17^a, 18^a underlie the sills of the body and prevent tipping of the body in either direction. However, if one of these sets of panels be swung downwardly to the position illustrated in Figure 3, the wagon body may tip in that direction, as indicated in said Figure 3. The movement of the panels to dumping position is effected by means of rods 20, which project at right angles from horizontal rods 21, the latter being provided with operating handles 22. When an operating handle 22 is moved, its rod 21 is rocked in its bearings 23 and the rods 20 which are passed through eyes 24 of the panels, throw the panels outwardly and downwardly.

It is to be understood that the invention is not limited to the precise construction set forth but that it includes within its purview whatever changes fairly come within either the terms or the spirit of the appended claim.

Having described my invention what I claim is:

In a device of the character described the combination with a running gear consisting of longitudinally extending side rails and transverse end rails, of supports hingedly connected to the longitudinally extending side rails, a horizontal operating rod, rods carried by the horizontal operating rod and projecting substantially at right angles thereto, eyes carried by the supports through which the last named rods project and in which said last named rods may move when the supports are swung outwardly and downwardly by rocking the horizontal operating rod, a body pivoted centrally and longitudinally upon cross bars of the running gear, and hinged sides for said body.

In testimony whereof he affixes his signature in the presence of two witnesses.

LOUIS P. WOOD.

Witnesses:

GEORGE W. MALCOLM,
GEORGE C. JOHNSON.
